UNITED STATES PATENT OFFICE.

JOHN ROBERT McLAREN, JR., OF MONTREAL, QUEBEC, CANADA.

SNOW-SHOVEL.

SPECIFICATION forming part of Letters Patent No. 368,102, dated August 9, 1887.

Application filed May 31, 1887. Serial No. 239,596. (No model.) Patented in Canada June 15, 1887, No. 26,953.

To all whom it may concern:

Be it known that I, JOHN ROBERT McLAREN, Jr., of the city of Montreal, in the district of Montreal and Province of Quebec, Canada, 5 have invented a certain new and useful Improved Snow-Shovel; and I do hereby declare that the following is a full, clear, and exact description of the same.

The object of my invention is to produce a snow-shovel composed of a separate blade and handle, which shall be lighter and stronger than those now in use, and at the same time very durable and cheaply constructed. I propose to effect this by bending the handle at its 15 junction with the blade, forking its end and carrying it underneath the blade nearly to the front or scraping edge, thus supporting it evenly under its whole surface instead of solely at the rear.

For full comprehension of the invention, reference must be had to the annexed drawings, in which—

Figure 1 is a perspective rear view of my invention; Fig. 2, a side view, and Fig. 3 a 25 top view.

Similar letters of reference indicate like parts.

A is the blade of the shovel flat on its upper side, B being the handle, which is, as shown 30 at B' in Figs. 1 and 2, bent at the junction with the shovel and split into two ends, b b, bearing the blade upon them, these being secured to the shovel by rivets c c.

D is a back piece or rib across the rear end of the shovel-blade A, secured on it by rivets 35 d d, and E is a clinching-rivet passing through rib D, blade A, and handle B.

It will be seen that by this construction a better leverage can be obtained in working, as the lift is effected entirely by the handle and 40 its integral continuation. The forked end and the blade simply afford a surface for the snow to rest upon.

I am aware that in the patent, No. 321,326, granted to H. D. Waite the handle is shown 45 as passing under the blade for the purpose of supporting it, but is particularly claimed as being double, and I therefore disclaim this construction.

What I claim is as follows:

1. The combination, in a snow-shovel, of the blade and a straight handle bent at its junction with the blade and attached to it in the center of the back, and having forked end diverging from such junction toward the front 55 corners of the blade, all as herein set forth.

2. The combination of the bent handle B, with forked end b b, blade A, secured thereon, and rib D, secured to blade and handle, all substantially as described.

JOHN ROBERT McLAREN, JR.
